UNITED STATES PATENT OFFICE

129,476

DESIGN FOR A DISPLAY CASE

Edward P. Gannon, Rockford, Ill.

Application June 21, 1941, Serial No. 101,598

Term of patent 7 years

To all whom it may concern:

Be it known that I, Edward P. Gannon, a citizen of the United States, residing at Rockford, in the county of Winnebago and State of Illinois, have invented a new, original, and ornamental Design for a Display Case, of which the following is a specification, reference being had to the accompanying drawing, forming part thereof.

In the drawing:

Fig. 1 is a front elevational view of a display case, showing my new design;

Fig. 2 is a side elevational view thereof; and
Fig. 3 is a top plan view thereof.

The dominant features of the design are shown in full lines.

I claim:

The ornamental design for a display case, substantially as shown and described.

EDWARD P. GANNON.
